UNITED STATES PATENT OFFICE

2,255,484

AUTOMATIC BACKGROUND CONTROL FOR
TELEVISION SYSTEMS

Robert B. Dome, Bridgeport, Conn., assignor to
General Electric Company, a corporation of
New York

Application November 30, 1938, Serial No. 243,134

7 Claims. (Cl. 178—7.5)

My invention relates to television systems and more particularly to a control arrangement for automatically inserting at a selected point in the television system that component of the picture signal which determines the background brilliancy of the transmitted picture. While not limited thereto, my invention is particularly suited for use in a television receiver for the automatic reinsertion of the picture signal background component which previously was removed at some point in the system during the amplification of the picture signal.

An object of my invention is to provide in a television system an automatic background control which permits a more economical use than heretofore possible of the several high voltage potential sources required for the operation of the electron discharge devices employed.

A further object of my invention is to provide in a television receiver having automatic background control an arrangement which enables the operation of the cathode element of a cathode ray picture tube, or other electron discharge device to which it may be desirable to supply automatic background potentials, near ground potential thereby dispensing with the necessity of carefully insulating the cathode and its source of energizing current from each other and from ground for relatively high values of potential in the manner heretofore necessary.

An additional object of my invention is to provide in a television system an automatic background control in which the background effect may be exaggerated to any desired degree as an aid to improving the contrast of the reproduced picture.

The novel features which I believe to be characteristic of my invention are set forth with particularity in the appended claims. My invention itself, however, both as to its organization and the method of operation, together with further objects and advantages thereof, will best be understood by reference to the following specification taken in connection with the single figure of the accompanying drawing which illustrates a television receiver embodying my invention.

Referring more particularly to the drawing, my invention is illustrated as embodying in a television receiver having an input circuit connected to an antenna 10 and ground 11. Television signals are supplied by the antenna and ground to receiving apparatus, represented conventionally by the rectangle 12, which may comprise radio frequency stages of amplification, a

frequency converter stage, intermediate frequency stages of amplification, a detector, and an arrangement for separating from the television signal the synchronizing impulses normally transmitted therewith and for developing from such impulses scanning potentials. The output of the detector included in the apparatus 12 may be amplified before being supplied through a condenser 13 to an electron discharge device 14 for additional amplification. The output of the amplifier 14 is supplied through a condenser 15 to the control electrode 16 of an electron discharge device which may, for example, be a cathode ray picture tube 17. The picture tube has deflecting electrodes 18, 19 to which are supplied through the respective conductors 20, 21 from the horizontal and vertical oscillators included in the apparatus 12 scanning or deflecting potentials. These potentials operate in a manner well-known in the art to produce a horizontal and vertical sweep of the picture modulated cathode stream across the fluorescent screen provided in the end of the picture tube thereby to reproduce the transmitted picture.

The overall or background brilliancy of the picture may be transmitted as a component of the picture signal. This however, requires the use throughout the television system of direct current amplifiers. Amplifiers of this type when used in this manner present considerable problems and have not been found economically feasible. For this reason, the receiving apparatus 12 customarily includes at least one stage of amplification which in its normal operation removes the background component, when transmitted, and amplifies only the picture signal component. It therefore becomes necessary in the television receiver to reinsert in an automatic manner the component of the television signal which determines the background brilliancy of the transmitted picture.

Automatic background control is accomplished in my invention in the following manner. A high resistance 22 is connected between the grid 23 and cathode 24 of the electron discharge amplifier 14. The picture signal is supplied through the condenser 13 to the grid 23 where a certain amount of rectification of the picture signal occurs by the grid 23 and the condenser 13 thereupon charges to bias the grid 23 with a negative potential. The bias voltage which is stored by the capacitor 13 leaks off by way of the resistor 22 (the time constant of the condenser and resistor being made approximately one-fifth of a second) and the magnitude of the bias volt-

age thus varies in accordance with the overall or background brilliancy of the transmitted picture. The picture signal which is supplied to the grid 23 has a maximum amplitude for white and a minimum amplitude for black. The grid 23 therefore has a relatively large negative bias when a white picture is transmitted and a relatively small negative bias during the transmission of a black picture. The average space current of the amplifier 14 varies in accordance with the bias on the grid 23 and consequently decreases when a white picture is transmitted. This space current flows through an impedance, which may be comprised by a resistor 25 and parallel connected condenser 26, connected between the cathode 24 and ground. It is evident that the potential appearing across the resistor 25 is large during the transmission of a black picture and is relatively small for a white picture.

The potential drop across the resistor 25 has a polarity as indicated on the drawing. This potential is impressed between the cathode 27 and the control electrode 16 of the cathode ray tube through a circuit which includes the resistor 29 and the left hand portion of the resistor 28. The bias on the control electrode 16 is determined by the potential drop across the resistor 25 at any time added with proper polarity to that across that portion of the resistor 28 to the left of the manually adjusted contact 30. It will be evident that a black picture produces a large potential drop across the resistor 25 and therefore biases the control electrode 16 negatively so that the average brightness of the picture reproduced on the cathode ray screen decreases as is proper for a black picture. A white picture, on the other hand, produces a much smaller potential across the resistor 25 thereby to allow the potential drop across the resistor 28 to bias the control electrode 16 more positively to increase the average brilliancy of the reproduced picture as is proper for a white picture. In this manner, the average brilliancy or background of the reproduced picture is automatically controlled in accordance with the overall or background brilliancy of the transmitted picture. The resistor 28 provides an initial adjustment on the picture brilliancy in order that the proper range of control may be obtained. This is effectively a manual background control.

My invention has several important advantages. The cathode 27 is operated near ground potential, and therefore requires only a minimum of insulation from ground for itself and associated circuit as well as for the source of current which is used to energize the cathode. An equally important advantage of my invention is that the operation of the cathode 27 near ground potential enables the most economical use possible to be made of the several high voltage sources of potential which are required for the electron discharge devices employed in the television receiver. That is, the source of anode potential required for the amplifier tubes may be connected in series with the source of relatively high potential required for the several anodes of the cathode ray picture tubes.

The exact manner by which the several sources of anode potential may be serially connected is disclosed and claimed in my patent application No. 237,785 filed Oct. 29, 1938, entitled High voltage supply circuit for television systems and assigned to the same assignee as the present invention.

This arrangement consists, briefly, in providing a secondary winding 31 in a power transformer 32, whose primary 33 is connected to a power source and in connecting the secondary winding to a full wave rectifier 34 whose output charges a condenser 35 through a suitable filter 36. The condenser 35 is charged to a potential of 200 to 300 volts to provide a source of anode potential for the amplifier 14 and for similar amplifier tubes included in the apparatus 12. The transformer winding 31 is also connected through the condensers 37 and 38 to a half wave rectifier 39. Current flows through the rectifier 39 during one-half cycle of the potential supplied by the transformer winding 31 to charge the condensers 37 and 38 substantially to the peak value of the secondary winding potential. The anode of rectifier 39 which is negative with respect to its cathode is connected through the resistance 41 to the positive terminal of the rectifier 34, thus causing an addition of potentials to appear across the capacitor 40. This, for example, may be of the order of 1,000 volts. The series circuit by which this additive voltage is attained may be traced from the grounded terminal of the condenser 40 through condenser 35, filter 36, a resistor 41, condenser 38, transformer winding 31, condenser 37, and a resistor 42, to the ungrounded terminal of the condenser 40.

The potential appearing across the condenser 40 is supplied through a conductor 43 and through the voltage dividers 44, 45 and 46 to the deflecting electrodes 18, 19 and the focusing electrode 47 which are provided in the cathode ray picture tube 17. The voltage dividers 44 and 45 have manually adjusted contacts 48 and 49, respectively, by which the high voltage potential supplied through the conductor 43 to the deflecting electrodes 18, 19 may be controlled to center the picture on the fluorescent screen provided in the end of the picture tube 17. The voltage divider 46 has a manually adjustable contact 50 by which the potential supplied to the focusing electrode 47 may be controlled for the purpose of controlling the size of the illuminated spot produced by the electron stream when it strikes the fluorescent screen.

The anode potential for the amplifier 14 is supplied through a resistor 51. In practice, the value of the resistor 51 is generally made approximately equal to the value of the resistor 25 in order that the direct current and alternating current amplifier characteristics of the amplifier 14 are substantially equal. A circuit embodying my invention may, however, be adjusted to yield exaggerated background effects by making the value of the resistor 25 larger than that of the resistor 51. The background effects may be minimized by making the value of the resistor 51 larger than that of the resistor 25. Under some conditions of operation, the exaggerated background effects may be desirable as an aid to improving the contrast of the reproduced picture.

While I have shown a particular embodiment of my invention, it will of course be understood that I do not wish to be limited thereto since many modifications may be made in the circuit elements and their arrangement, and I contemplate by the appended claims to cover all such modifications as fall within the true spirit and scope of my invention.

What I claim as new and desire to secure by Letters Patent of the United States is:

1. The combination, in a television receiver having automatic background control, of a

source of picture signals, means for amplifying said signals, said means including an electron discharge device having a cathode and an anode and two impedances connected therebetween, one of said impedances being adapted to develop thereon high frequency voltage representing the received picture and the other having substantially zero impedance for high frequency currents representing said picture and adapted to develop thereon voltages varying only with the background brilliance of the transmitted picture, a picture reproducing device having a cathode and control electrode, a path impenetrable to unidirectional current extending from said control electrode through both of said impedances to the cathode of said picture reproducing device, and a unidirectional current conducting path extending from said control electrode through the last mentioned of said impedances, but excluding the first mentioned of said impedances, to said cathode, the said last mentioned impedance being poled in said last mentioned path to provide a bias on said picture reproducing device varying with said background brilliance.

2. The combination, in a television receiver, of an electron discharge amplifier, an electron discharge picture reproducing device, said amplifier and device each having a cathode, an anode and a control electrode, a source of picture signals and background signals connected between the grid and cathodes of said amplifier, a coupling impedance between the anode of said amplifier and ground adapted to develop thereon potentials in accordance with said picture signals, means to supply said potentials to the grid of said device, a resistance connected between ground and both of said cathodes and by-passed for picture signals, means to produce on said resistance a potential variable with said background signals, and a bias connection exclusive of said first mentioned coupling impedance between the grid of said device and ground whereby the potential on said resistance is supplied between the grid and cathode of said device as a bias.

3. The combination, in a television receiver, of an amplifier having an anode, a cathode, and a control electrode, an electron discharge picture reproducing device having a control electrode, a cathode, and a high potential electrode, a source of operating potential for said amplifier having one terminal connected through a picture signal coupling impedance to the anode of said amplifier and its opposite terminal connected to both of said cathodes through a background signal coupling impedance, said high potential electrode being connected through a source of operating potential and said background coupling impedance to both of said cathodes, a unidirectional current conducting path between said control electrode and cathode of said picture reproducing device including said background signal coupling impedance, means to supply picture signals from said picture signal coupling impedance between said control electrode and cathode of said reproducing device, and means to produce both picture signals and background signals on the control electrode of said amplifier whereby said signals are amplified thereby and supplied between the control electrode and cathode of said picture reproducing device.

4. The combination, in a television receiver of an amplifier having an anode, a cathode, and a control electrode, an electron discharge picture reproducing device having a cathode and a control electrode, a source of operating potential

having one terminal connected through a picture signal coupling impedance to said anode of said amplifier and its opposite terminal connected through a background coupling impedance to both of said cathodes, means to maintain said opposite terminal and said control electrode of said picture reproducing device at substantially fixed unidirectional potential while said cathodes vary in potential by reason of variations in potential on said background coupling impedance, a connection for picture signals between the anode of said amplifier and the control electrode of said picture reproducing device, and means to supply both picture signals and background signals between the control electrode and cathode of said amplifier whereby they are amplified and said picture signals are supplied between said terminal at fixed unidirectional potential and the control electrode of said picture reproducing device and said background signals are supplied between said terminal at fixed unidirectional potential and the cathode of picture reproducing device.

5. The combination, in a television receiver, of an electron discharge amplifier having an anode, a cathode, and a control electrode, a picture reproducing discharge device having a cathode, control electrode and a high potential electrode, a source of energizing potential having one terminal thereof connected to both of said cathodes through a resistance and other terminals thereof positive with respect to said one terminal connected respectively to said anode through an impedance and to said high potential electrode, means to by-pass said resistance with respect to picture currents having frequencies higher than variations in average brilliance of the transmitted picture, a control electrode circuit for said amplifier adapted to have impressed thereon the received television signal and including means to produce a voltage on said grid which varies negatively with respect to the cathode in accordance with the average brilliance of the transmitted picture whereby the voltage on said resistance varies with said average brilliance of said picture, a bias connection for unidirectional currents from the control electrode of said picture reproducing device to the negative terminal of said resistance, and means to supply picture signal electromotive force existing between said negative terminal of said resistance and said anode to said control electrode of said picture reproducing device.

6. The combination in a television receiver, of an amplifier having a cathode, a control electrode, and an anode, a picture reproducing device having a cathode, and a control electrode, and means to transmit both picture and background signals through said amplifier while operating said cathodes at substantially the same unidirectional potential, said means comprising means connecting said cathodes together for unidirectional currents and to ground through a background coupling impedance, a picture signal coupling impedance connected between said anode of said amplifier and ground whereby said coupling impedances are in series between the anode and cathode of said amplifier, means connecting the control electrode of said picture reproducing device to said anode of said amplifier for picture signals and to ground for unidirectional current, and means to supply alternating picture signals and negative bias potential varying with the average intensity thereof to the control electrode of said amplifier whereby the

potential between the control electrode and cathode of said picture reproducing device varies with both picture and background signals, and said cathodes vary from ground only by the potential on said background coupling impedance.

7. The combination, in a television receiver, of a picture reproducing device having a high potential electrode, a control electrode and a cathode, an amplifier having a cathode, a control electrode and an anode, a source of unidirectional operating potential having its negative terminal connected to both of said cathodes through a background signal coupling impedance and to the control electrode of said picture reproducing device through a unidirectional current path, 15

and having its positive terminal connected to said high potential electrode, additional picture signal coupling means between said anode of said amplifier and the control electrode of said picture reproducing device, means to supply picture signals to said control electrode of said amplifier for reproduction by said picture reproducing device, and means to produce on said control electrode of said amplifier a bias varying negatively with respect to said cathode in accordance with background signals thereby to vary the potential on said background coupling impedance and between the cathode and control electrode of said picture reproducing device.

ROBERT B. DOME.
